Des. 226,285
Patented Feb. 6, 1973

226,285

INTERLOCKING TRAY

Robert F. Bateman, St. Paul, Minn., assignor to
Plastics, Inc., St. Paul, Minn.

Filed June 9, 1971, Ser. No. 151,626

Term of patent 14 years

Int. Cl. D7—99

U.S. Cl. D44—10 E

FIG. 1

FIG. 2

FIG. 3

FIG. 1 is a top plan view of an interlocking tray, showing my new design;

FIG. 2 is a side elevational view; and

FIG. 3 is a top perspective view thereof.

The bottom of the design is substantially plain and unornamented.

I claim:

The ornamental design for an interlocking tray, as shown and described.
